UNITED STATES PATENT OFFICE

GUSTAV W. WEGNER, OF CHICAGO, ILLINOIS

MATCH-BOX HOLDER

Application filed May 10, 1928. Serial No. 276,535.

This invention relates to a base upon which to place a match box of the sliding tray type, and particularly a holder having a core-piece or pusher which fits within the jacket for the box and displaces the tray therefrom when the box is placed in position upon the holder.

The object of the invention is to provide a very cheap and simple device for the purposes stated, and one which will securely grip 10 the jacket for the box and prevent its being lifted from the holder in case the box instead of the holder is grasped for the purpose of lifting the holder, and incidentally render it sufficiently difficult to separate the box from 15 the holder to discourage appropriating the whole box of matches.

It has heretofore been proposed to spin or otherwise form from thin metal, a dome-shaped support for a match box, and to sub- 20 divide the dome into two side walls between which the jacket of the box may be placed, and a displacer in position to extrude the tray when the box is placed in position. But the intermediate portion of the dome in 25 the proposal heretofore made for producing a match box holder of this kind was severed and refashioned in a way to produce a pair of tongues as the tray displacing means, and cause these tongues to largely lose their co- 30 operation with the outer walls and therefore have insufficient gripping faces upon the box.

As compared with this, the present invention forms a dome of suitable dimensions with kerfs or cuts in vertical planes through the 35 dome a distance equal to the proportion of the length of the match box jacket that is to be received in the dome, and spaced apart a distance that will leave on the outside of the box two edged gripping jaws, and on the 40 inside of the box as an undisturbed segment of the original dome, a displacing core, the edges of which, resulting from the cutting of the thin metal, will remain throughout in alignment with the edges of the adjacent por- 45 tions of the metal from which they were severed, so that the device constitutes an inner sharp edged jaw, which incidentally serves as the tray-displacing element and two co-acting outer sharp edged jaws; and these 50 jaws, by reason of the selected gauge of the

kerf or slots, will bite firmly into the walls of the match box jacket and render it so difficult to remove the match box from the holder that the inconvenience of appropriating the whole box of matches will be largely 55 remedied.

In the accompanying drawing—
Figure 1 is a top plan view of the holder, minus the match box; and

Figure 2 is a vertical axial section in a plane involving the minor transverse dimension of the match box and showing the match box in place.

1 represents the dome, 2 the slots or kerfs formed therein to produce an inner combined displacer and gripping jaw 3, and two outer coacting gripping jaws 4, the spacing of the kerf corresponding substantially to the minor transverse dimension of a conventional sliding tray match box, and the metal 35 which constitutes the jaws 3 and 4 being left in its original position so that the edges of said portions will stand in occluding or cooperative gripping relation and will so firmly bite upon and bind the jacket of the 40 match box that the box can with difficulty be removed. While the jaws 4 by reason of their convex sections, will have substantial rigidity even when made of very thin metal, they nevertheless have slight resiliency in 45 admitting the walls of the box; and the middle jaw and displacer 3 will retain sufficient convexity to resist its displacement from the intended relation to the jaws 4.

5 represents a tray which is preferably 50 formed from the same piece of metal as the dome 1, and 6 is an ornamental band preferably of an integral piece of metal confined between the shoulders 8 and 9 of the tray 55 and located in such position by first forming the shoulder 8 and then after the band 6 is put in position, spinning or otherwise forming the shoulder 9 above the band. As suggested at one side, band 6 may be made the 60 means of applying a finger hold 10, if desired.

The match box holder herein described may be made of any material suitable for the purpose, and by various processes, such 65

as spinning, drawing, stamping, casting, etc.

I claim:

1. A holder for match boxes of the sliding tray type, comprising a dome having a diameter approximately equal to the major transverse dimension of the jacket of the box; said dome being slotted in two planes corresponding in position to the walls which define said minor dimension and thereby providing an intermediate jaw and two cooperating outer jaws, the intermediate jaw being in position to extrude the tray of the match box, and the edges of the jaws remaining in the position which they held in the original metal of the dome whereby they stand opposite each other and in occluding or gripping relation to the walls of the box.
2. A match box holder comprising a cylindrical dome having an external diameter substantially equal to the distance between the narrow side walls of the match box, said dome having two slots parallel to the longitudinal axis thereof and adapted to receive the broad side walls of the match box.

25 Signed at Chicago, Illinois, this 8th day of May, 1928.

GUSTAV W. WEGNER.
